UNITED STATES PATENT OFFICE.

RENE W. BOULLET, OF OAKLAND, CALIFORNIA.

SAW SETTING AND FILING MACHINE.

1,245,430.

Specification of Letters Patent.

Patented Nov. 6, 1917.

Application filed December 27, 1913. Serial No. 809,084.

To all whom it may concern:

Be it known that I, RENE W. BOULLET, citizen of the United States, residing at Oakland, in the county of Alameda and State of California, have invented certain new and useful Improvements in Saw Setting and Filing Machines, of which the following is a specification.

This invention relates to an improved saw setting and sharpening machine.

An object of the invention is to provide a machine by which saws may be set and filed at a single operation, and automatically fed through the machine as the setting and filing proceeds.

Said invention consists, generally speaking, in mechanism for effecting the setting, mechanism for effecting the filing, mechanism for effecting the feeding, and devices for adjusting and manipulating the several parts.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:—

Figure 1 is a side elevation, partly broken away, of a machine constructed in accordance with the present invention;

Fig. 2 is a similar view looking at the reverse side from that disclosed in Fig. 1;

Fig. 3 is a longitudinal sectional view;

Fig. 4 is a view similar to Fig. 3, the filing mechanism having been removed;

Fig. 5 is a section on the line 5—5 of Fig. 3;

Fig. 6 is an end view of the machine;

Fig. 7 is a section on the line 7—7 of Fig. 1;

Fig. 8 is an enlarged elevation illustrating the detail construction of the saw setting mechanism;

Fig. 9 is a section on the line 9—9 of Fig. 8;

Fig. 10 is a section on the line 10—10 of Fig. 8;

Fig. 11 is a top plan view of the mechanism employed for operating the saw file;

Fig. 12 is a side elevation of a portion of the mechanism illustrated in Fig. 11; and

Fig. 13 is an enlarged elevation of the pawl and ratchet mechanism employed for the purpose of automatically advancing the carriage.

Referring now to the drawings wherein is illustrated the preferred form of my invention the numeral 1 designates substantially U-shaped supports between the extremities of which a pair of duplicate rack bars 2 are clamped, the clamping operation being effected through the medium of thumb screws 3 carried by the supports 1 and engaging extensions 4 of the said rack bars, the latter being designated as an entirety by the said numeral 2. A head portion 5 is formed integrally with each rack bar, the said head portion being disposed to extend at an angle 65 to the depending portion 4 and to engage a longitudinal groove 6 formed within the base portion 7 of the carriage employed in connection with the present invention.

The carriage is divided longitudinally as 80 is illustrated to advantage in Figs. 6 and 7 of the drawings and has secured at each end thereof clamping blocks 8, each of which is provided with an extension 9 having gage screws 10 adjustable thereupon, one of the 85 said screws terminating in a pointed extremity and the other of the said screws terminating in a recessed extremity within which the said pointed extremity is seated, this arrangement providing for minute adjustment of the sections of which the carriage is composed. Lateral adjustment of the said sections is effected through the medium of an adjusting screw 11 extending transversely through the blocks 8 and having 90 threaded upon each extremity a suitable knob 12, the manipulation of which will move the said carriage sections toward or away from each other as occasion demands.

Adjacent one end of the carriage, and upon each carriage section, I provide an upright 13 terminating in a bifurcated extremity 14 within which detachable bearings 15 are seated, the latter being maintained immovable during the operation of the device, by means of set screws 16 disposed for engagement therewith. A shaft 17 is journaled within the bearings 15, the said shaft having keyed or otherwise fixedly secured thereto, at one end thereof, a sprocket wheel 18, thus providing, in a manner to be herein-after fully described, for the rotation of

the said shaft. Comparatively large eccentrics 19 are secured to the shaft 17, one eccentric being disposed adjacent each bearing 15. Smaller eccentrics 20 are secured 5 to the said shaft, the said smaller eccentrics being either integral with or independent of the larger eccentrics 19. A ring or band 21 is arranged over the periphery of the smaller eccentrics 20, the said ring having 10 pivotally secured thereto as at 22 at diametrically opposite points links 23, the opposite extremities of which are pivoted as at 24 to sleeves 25 one of which is mounted for sliding engagement upon a screw rod 15 26 extending transversely of the links 23. An expansion spring 27 is arranged to embrace the rod 26 between the sleeves 25, the ends of the said spring abutting the said sleeves to normally exert outward pressure 20 thereupon. A thumb nut 28 is threaded upon the rod 26 to provide for adjustment of the sleeves, the purpose of the adjustment being apparent upon further reading of the specification. Pivoted as at 29 to 25 each sleeve 25 is a link 30, each link terminating at a point 31 where it is in turn pivoted to a reciprocating block 32, the said block having lateral extensions 33 formed integrally therewith and adapted 30 for engagement with vertical grooves 34 formed within suitable guides 35 in turn formed integrally with or secured to the inner face of one of the uprights 13.

A lip 36 is formed upon each block 32 at 35 its lower extremity, the said lip being disposed for engagement with a bell crank 37 pivoted as at 38 between lugs 39 formed integrally with or secured to adjustable blocks 40. To normally maintain the said lever 37 40 in engagement with the lip 36, a coiled spring 41 has been provided, one end of the spring being disposed for engagement with the said lever and the opposite end for engagement with the said block 40, the spring 45 intermediate its ends, being coiled about the pin upon which the lever 37 is pivoted. An opening 42 is formed within the block 40 between the lugs 39 through which the opposite end of the lever 37 from that engaging 50 the lip 36 depends, the said opposite end being seated within a cut-out 43 formed within a reciprocating anvil block 44, the latter being supported upon the base portion 7 of the carriage and within a groove 55 45 formed within the block 40. The inner extremity of the anvil block 44 is beveled as at 46 to act upon the saw teeth to be set in a manner to be hereinafter fully described.

60 The anvil block operating mechanism above described is the same at each side of the carriage, the anvils however are disposed out of alinement so as to act upon the saw teeth in the desired manner. By the 65 rotation of the shaft 17, it is apparent that

the anvils 44 are reciprocated simultaneously and that the teeth of the saw, disposed in the path thereof, are alternately bent or set in the desired manner.

Each anvil supporting block 40 is adjustable, such adjustment being effected through the medium of a lever 47, one end of which is fixedly secured to a shaft 48 journaled within an enlargement 49 formed at the base of each upright 13. The inner end of each 70 shaft has secured thereto a pawl 50 the free end of which is adapted for engagement with one of the blocks 40 for sliding the same upon the base portion 7 of the carriage according to the movement of the lever 47. 75 Notches 51 are formed upon the outer face of each upright 13 within any one of which a knob 52 carried by the lever 47 may be seated, the said notches being positioned in the arc of a circle described from the longitudinal axis of the shaft 48. To limit the sliding movement of the blocks 40, lugs 53 are provided, the said lugs being disposed in the path of the blocks 40 and for engagement with recesses or cut out portions 54 80 formed therein. If desired, the lugs of the respective blocks may be connected by means of a bridge plate 55, the latter serving in the capacity of a guide for the said blocks 40 during their sliding movement. 95

Upon each side of the carriage, I provide a lateral extension 56 adjacent which is pivoted as at 57 an operating lever 58 the free end of which is normally maintained in spaced relation to the extension 56 by means 100 of a spring 59 interposed therebetween. The inner end of the lever is pivoted as at 60 to movable securing blocks 61, the adjacent edges of which are normally disposed to extend parallel as is illustrated to advantage 105 in Fig. 5 of the drawings to thus secure or clamp the saw acted upon therebetween. The remote edges of the block 61 are cut at an angle as indicated at 62 whereby movement of the said blocks in one direction is limited. 110 To operate the blocks, during the arrangement of a saw therebetween, the levers 58 are forced toward the extensions 56 of the carriage causing the said blocks to move, one away from the other. After arranging the 115 saw therebetween, the levers 58 are released thus permitting the springs 59 to return the said blocks to their normal position whereupon the adjacent edges will engage lightly the opposite faces of the saw. The blocks 61 120 only engage the saw to such an extent as to obviate the bending movement of the saw when acted upon by the sharpening element and of course permit the said saw to move longitudinally between the blocks. 125

Passing on to the description of the mechanism employed for imparting movement to the carriage, 63 designates a suitable shaft having a ratchet wheel 64 mounted upon one end thereof, the teeth of the said ratchet 130

being engaged between a pivoted spring pressed pawl 65 carried by a movable bracket 66 loosely mounted upon the said shaft 63. An extension 67 is formed integrally with 5 the bracket 66, to the extremity of which an arm 68 is secured as at 69. The arm extends forwardly and terminates in a right angled extension 70 between which and a similar extension 71 also carried by the said arm, a 10 spring 72 is interposed, the said spring being arranged to embrace a rod 73 slidable with respect to the extensions 70 and 71, the said rod being secured as at 74 to an ear 75 formed integrally with an adjustable bracket 15 76 movable vertically upon a rocker frame designated as an entirety by the numeral 77, the said frame being pivoted, the shafts 48 above mentioned serving as pivots therefor. Vertical adjustment of the bracket 76 is ef- 20 fected through the medium of a screw rod 78 operable by means of a thumb nut 79 mounted upon one end thereof. A yoke 80 connects the two vertical sections of which the frame 77 is composed. One of the sec- 25 tions, the one to which the rod 73 is secured, has secured thereto in any suitable manner, an arm 81 the opposite end of which is pro- 30 vided with an elongated opening 82 within which a pin 83 works, the latter being sup- ported by means of a link 84 arranged to em- 35 brace a suitable shaft 85, square in cross sec- tion, and journaled within bearings 86 pro- vided therefor. A spring 87, one end of 40 which is secured to the pin 83, and the oppo- site end to a pin 88 projects from the said 45 arm 81 and is provided to normally main- tain the said pin in engagement with one 50 end of the slot.

As a means for imparting movement to 40 the rocker frame 77, I provide arms 89 one end of which is secured as at 90 to exten- 45 sions 91 formed one upon each of the rocker frame sections, the opposite ends terminating in bands 92 arranged to embrace or engage 50 the periphery of the large eccentrics 19 mounted upon the shaft 17 above referred to. From the above arrangement it is ap- 55 parent that by the rotation of the shaft 17, the frame 77 is rocked upon its pivot formed by the shafts 48.

The opposite section of the rocker frame 77 from that having the rod 73 secured thereto is in substance, a duplicate of the section above described, the same comprising 55 a screw rod 93, bracket 94 and thumb nut 95. Secured as at 96 to the bracket 94 is an arm 97 the opposite end of which is pivoted as at 98 to a cam 99 mounted upon the shaft 85 at its opposite end from that engaged by the 60 link 84. A pin 100 projects inwardly from the cam 99, the purpose of the pin being hereinafter fully described.

Upon the shaft 63 and rotatable there- 65 with I provide a pair of serrated blocks 101, the serrations being arranged in series, the

said series being so arranged as to provide for the gaging of the carriage movement according to the pitch of the saw acted upon. A pawl 102 is movable with the shaft 85, the said pawl being slidable 70 throughout the length of the said shaft, its free end engaging the serrations of the blocks 101 to limit rotation of the said blocks according to the adjustment of the said pawl. Graduation marks 103 may be 75 provided upon the shaft 85 to facilitate proper adjustment of the said pawl. Between the blocks 101 of the shaft 63 and disposed for engagement with the rack bars 2 I provide a pair of uniformly spaced gear 80 wheels 104, one wheel being disposed for engagement with each rack bar 2, such en- gagement providing for the sliding move- 85 ment of the entire carriage according to the rotation of the shaft 63 upon which the said wheels 104 are mounted.

At the opposite end of the carriage from that upon which the uprights 13 are formed, uprights 105 are provided, one upright at each side of the carriage. Each upright 90 terminates in a bifurcated end 106 to pro- 95 vide for a removable mounting of bearings 107, the latter having a shaft 108 journaled therein. Set screws 109 are adapted to maintain the said bearings 107 in the bifur- cations provided therefor. Upon one end 100 of the shaft 108 is mounted a pulley 110, through the medium of which, motion is transmitted from any suitable source of power to the entire machine, the opposite end of the shaft 108 having mounted there- 105 upon a hand operated wheel 111 to provide for the manual operation of the machine if so desired. Between the bearings 107, the shaft 108 serving as a pivotal support, I 110 provide an oscillatable frame 112 terminat- 115 ing at its free end in a head portion 113 having graduation marks 114 formed there- upon. Extending transversely of the head 113 is a removable spindle 115 terminating at its lower extremity in a disk like base 116 having a recessed lower face 117. The base 116 is enlarged as at 118, the said enlarge- 120 ment serving as a bearing for a shaft 119 upon one end of which a circular file 120 is 115 mounted, a thumb screw 121 being provided to maintain the said file upon the said shaft. A bracket 122 is formed integrally with the enlargement 118 to provide, an additional 125 bearing for the shaft 119. Between the bracket and the enlargement and mounted upon the said shaft 119 is a beveled gear 123 adapted for engagement with a like gear 124 mounted for rotation upon the spindle 115 and having a recess 125 formed therein 125 within which the base 116 of the said spin- 130 dle is seated. Bearing-balls 126 are pro- vided, wherever necessary, to facilitate the rotation of the several gears. The said gear 124 is also disposed for engagement

with a beveled pinion 127 mounted upon a shaft 128 journaled within bearings formed by the head 113 and an enlargement 129 of the frame 112. A second pinion 130 is 5 mounted upon the shaft 128 adapted for engagement with a beveled gear 131 mounted upon the shaft 108, this engagement transmitting the rotary movement of the said shaft 108 to the several gears and pinions 10 above referred to and finally to the circular file 120. The spindle 115 is angular in cross section at one end and has arranged there-over a plate member 132 whereby movement may be imparted to the said spindle to provide 15 for the angular adjustment of the file 120. To ascertain the desired adjustment a lip 133 is formed integrally with the plate 132, the said lip being disposed for engagement with the head 113 and particularly the graduated or notched portion 114 thereof. A thumb nut 134 is provided to support the spindle in the proper position necessary to 20 operation.

Secured to the frame 112 at one side 25 thereof and depending therefrom I provide a specially formed plate member 135 having a notch 136 formed therein at a point adjacent its lower extremity. The pin 100 above referred to is adapted for engagement with the said plate 135 and the notch 136 to oscillate the frame 112 and the mechanism carried thereby during a rocking of the frame 77. A sprocket 137 is mounted upon the shaft 108 over which a suitable sprocket 30 chain 138 is arranged, the said chain being also disposed for engagement with the sprocket 18 to transmit motion to the shaft 17 necessary to the operation of the machine.

The structure of the machine having been 40 described in detail, it now remains to set forth the operation thereof. The band saw acted upon, the teeth having already been cut, is first clamped between the rack bars 2 by manipulating the thumb screws 3, the 45 toothed edge of the saw being disposed upon a plane slightly above the teeth of the rack bars 2 in the path of the anvils 44. The carriage is then set so that the said anvils will engage, during operation, the teeth at one 50 end of the saw, whereupon motion is imparted to the machine by driving the pulley 110 or the hand wheel 111. The shaft 108 upon which the wheels 110 and 111 are mounted being connected to the shaft 17 by 55 means of the sprocket chain 138, it is apparent that the said shaft 17 is rotated causing the eccentrics 19 and 20 to be actuated and a rocking or oscillatory motion imparted to the frame 77 as well as a reciprocatory 60 movement imparted to the blocks 32. Movement of the blocks 32 will actuate the bell cranks 37 and reciprocate the anvils 44, causing the latter to engage the teeth of the saw and bend or set the same in the desired 65 manner, this being accomplished by reason

of the engagement between the beveled extremities 46 of the anvils and the said saw teeth. The anvil carrying blocks 40 may be adjusted so as to act upon saws varying in pitch, this being effected by manipulation 70 of the lever 47, as it is apparent upon reference to Figs. 8 and 9 of the drawings that the said blocks 40 may be moved by reason of the engagement of the pawl 50 therewith. The lugs 53 limit the movement of the said 75 blocks. The length of the reciprocatory stroke of the blocks 32 may be varied by adjusting the thumb nut 28 upon the rod 26, for instance, when it is desired that the stroke should be lengthened, the said thumb nut 28 is rotated so as to compress the spring 27 and move the sleeves 25 into closer proximity and thereby increase the distance between the pivot point 31 and the eccentric 20. To shorten the length of the stroke, a 80 reverse operation of the thumb nut should be effected.

The rocker frame 77 being pivoted as at 48 and connected to the shaft 17 through the medium of the eccentrics 19 and arms 89, it is apparent that oscillatory movement is imparted to the said frame during the rotation of the shaft. The frame, at one side, is connected to the shaft 63 by means of the rod 73, arm 68 and bracket 66, the latter 90 having a spring pressed pawl 65 pivoted thereon to rotate the shaft 63 by reason of the engagement between the said pawl and the ratchet 64 carried by the said shaft. The gear wheels 104 being mounted upon the 95 shaft 63, it is apparent that the entire carriage is moved longitudinally with respect to its supporting structure by reason of the engagement between the said gear wheels and the teeth of the rack bars 2. To adjust the step by step movement of the carriage, the pawl 102 should be shifted upon the shaft 85 so as to engage any one of the 100 several series of serrations formed upon the blocks 101, thereby limiting the rotary movement of the shaft 63 during the operation of the device.

Simultaneous with the step by step movement of the carriage, an oscillatory movement is imparted to the frame 112, this being accomplished by reason of the engagement between the pin 100 and the plate member 135 depending from the said frame. The cam 99 to which the pin 100 is secured being movable with the frame 77 and the 115 shaft 85, it is apparent that the frame 112 will be raised and lowered simultaneously with the oscillation of the frame 77. The movement of the frame 112 will raise and lower the circular file 120 respectively out of and into engagement with the teeth of the saw, and as the said file is driven from the shaft 108 through the chain of gears provided therefor, it is apparent that the teeth of the saw may be filed or sharpened 120

as occasion demands. By the simultaneous oscillatory movement of the frame 77 and the frame 112, the file 120 is raised from engagement with the saw acted upon during 5 the forward movement of the carriage, and as the carriage moves sufficiently to position the teeth thereof from engagement by the anvils 44, it will be observed that only every other tooth of the saw is filed.

10 Angular adjustment of the circular file 120 may be effected by adjusting the plate member 132, the degree of adjustment being ascertainable by the relative position of the lip 133 with respect to the graduations or notches 114 of the head 113 of the frame.

It being necessary that the pawl 102 should be removed from engagement with the serrations of the blocks 101 during the 20 step by step movement of the carriage, means have been provided for actuating the said pawl, such means comprising the arm 81, one end of which is secured to the frame 77 and the opposite end to a link 84 in turn 25 secured to the shaft 85 upon which the pawl is mounted for sliding movement. The spring 87 serves as a cushion to yieldably maintain the pin 83 of the said link in engagement with one end of the slot 82 of the 30 said arm 81.

The carriage having been moved until all of the teeth of the saw have been set by the anvil blocks 44, and every other tooth sharpened by the file 120, a second step by step 35 operation of the carriage is necessary to provide for a sharpening or filing of the saw. During a second operation, the anvils 44 are rendered inoperative by adjusting the thumb nuts 28 upon the rods 26, thus permitting 40 the file 120 to be raised and lowered so as to engage every other tooth of the saw and thus sharpen the same in a manner similar to that above described.

By the manipulation of the thumb nut 79 45 it is apparent that the position of the bracket 66 may be varied, as the arms 68 and 73 connecting the said bracket 66 with the rocker frame 77 are so arranged as to be adjusted vertically with respect to the rocker 50 frame. The manipulation of the thumb nut 95 will, in a manner similar to that just described, vary the position of the bracket 94 and accordingly increase or diminish the pivotal movement of the cam 99.

55 Lateral adjustment of the sections of which the carriage is composed is effected through the operation of the thumb nuts 12 and gage screws 10.

It will be further seen that the machine is 60 so timed that the movement of the carriage and the setting of the teeth follow in exceedingly rapid succession, so that it requires only a minimum amount of time to properly set and sharpen the saw.

60 In reduction to practice, I have found

that the form of my invention, illustrated in the drawings and referred to in the above description, as the preferred embodiment, is the most efficient and practical; yet realizing that the conditions concurrent with the 70 adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. In a machine for setting and sharpening saws, laterally adjustable rack bars adapted to clamp the saw acted upon there-between, a traveling carriage mounted upon said rack bars, means forming a part of said carriage adapted for engagement with said rack bars for moving the former, saw setting mechanism operable during movement of said carriage, and saw sharpening mechanism operable simultaneously with said setting mechanism, as and for the purpose set forth.

2. In a machine of the character described, a traveling carriage, anvil blocks simultaneously reciprocable upon said carriage, means operable simultaneously with the operation of the said anvil blocks for moving said carriage, and means including a plurality of eccentrics connected respectively to the said blocks for simultaneously reciprocating the 100 same, as and for the purpose set forth.

3. In a machine of the character described, a traveling carriage, a support for said carriage, adjustable anvil blocks movable with said carriage, a driven shaft mounted upon said carriage, eccentrics rotatable with said shaft, and means for adjustably connecting the said eccentrics with the said anvils for reciprocating the latter according to the rotation of the said shaft, as and for the purpose set forth.

4. In a machine of the character described, a pair of laterally reciprocable anvil blocks, the said blocks being disposed oppositely and out of alinement one with the other, means 115 for adjusting the said blocks, a driven shaft, eccentrics movable with said shaft, a pair of vertically reciprocable blocks, adjustable means connecting the said vertically movable blocks respectively with the said eccentrics, and means including a bell crank adapted for engagement with one of the said vertically reciprocable blocks, and one of the said anvil blocks for imparting movement of the one to the other according to the rotation of the said shaft.

5. In a machine of the character described, the combination with a traveling carriage, a saw carrying support for said carriage, the teeth of the saw being disposed in a 130

plane above the face of said carriage, of a pair of reciprocable anvil blocks movable with said carriage, the said blocks adapted to be moved into and out of engagement 5 with the teeth of the said saw, a bell crank adapted for engagement with each anvil block, and means carried by and operable during the movement of said carriage for actuating said bell crank, as and for the 10 purpose set forth.

6. In combination with a machine of the character described, a pair of reciprocable anvil blocks, a bell crank adapted for engagement with each block, a pair of vertically reciprocable blocks, the said last mentioned block being disposed for engagement with said bell crank, a driven shaft, eccentrics mounted upon said shaft, and adjustable means including a plurality of links 15 connecting the said eccentrics respectively with the said vertically movable blocks for increasing or diminishing the length of the reciprocatory stroke thereof, as and for the 20 purpose set forth.

7. In combination with a machine of the character described, reciprocable anvil blocks, driven eccentrics, means including a plurality of links connecting the said eccentrics with the said blocks, a screw rod, 25 sleeves adjustable thereupon, the said links being pivotally connected to the said sleeves, and means adjustable upon said rod adapted 30 for engagement with said sleeves for varying the length of the reciprocatory stroke 35 of the said blocks, as and for the purpose set forth.

8. In combination with a machine of the character described, a pair of reciprocable anvil blocks, means for reciprocating the

said blocks, a block member having a groove 40 formed therein within which the said anvil blocks are arranged, and means including a pivoted pawl adapted for engagement with the said block member for varying the position of the said anvil blocks, as and for 45 the purpose set forth.

9. In a machine of the character described, the combination with saw setting mechanism, and an oscillatable frame operable during the operation of said setting mechanism, a second oscillatable frame, a file carried thereby, and means connecting the said first mentioned oscillatable frame with the said file carrying frame for raising and lowering the latter into and out of engagement 50 with the saw acted upon during the operation of the said setting mechanism.

10. In a machine of the character described, the combination with saw setting mechanism, of a rocker frame operable during the operation of said setting mechanism, of a driven shaft, a frame oscillatable upon said shaft, a circular file carried by said frame, means for rotating the said file according to the rotation of said driven shaft, 65 and means carried by said first mentioned frame and adapted for engagement with said second mentioned frame for raising and lowering the latter into and out of engagement with the saw acted upon, as and for 70 the purpose set forth.

In testimony whereof I affix my signature in presence of two witnesses.

RENE W. BOULLET.
